UNITED STATES PATENT OFFICE

127,007

DESIGN FOR A WINE BOTTLE

Ronald H. Dallas, South Gate, Calif., assignor to Glass Containers, Inc., Los Angeles, Calif., a corporation of California

Application December 16, 1940, Serial No. 97,358

Term of patent 7 years

To all whom it may concern:

Be it known that I, Ronald H. Dallas, a citizen of the United States, residing at South Gate, in the county of Los Angeles and State of California, have invented a new, original, and ornamental Design for a Wine Bottle, of which the following is a specification, reference being had to the accompanying drawing, forming part thereof.

Fig. 1 is a side elevational view of a wine bottle
embodying my new design;

Fig. 2 is an elevational view taken from the right of Fig. 1; and

Fig. 3 is a top plan view thereof.

I claim:

The ornamental design for a wine bottle, as shown.

RONALD H. DALLAS.
